UNITED STATES PATENT OFFICE.

ELMER J. MANNING, OF JANESEVILLE, WISCONSIN.

ATOMIZER.

1,278,187.

Specification of Letters Patent. Patented Sept. 10, 1918.

Application filed August 6, 1914. Serial No. 855,449.

To all whom it may concern:

Be it known that I, ELMER J. MANNING, a citizen of the United States, residing at the city of Janesville, county of Rock, and 5 State of Wisconsin, have invented new and useful Improvements in Atomizers, of which the following is a specification.

My invention relates to improvements in atomizers. The object of my invention is 10 to provide an auxiliary device for atomizing or converting liquid fuel arising from condensation, as it is being used in an engine for power purposes, into a fine spray, whereby the same is used with greater economy 15 and efficiency. Experience has demonstrated the fact that when liquid fuel is being used in an engine a quantity of the heavier gasoline or other liquid fuel is liable to settle and accumulate in the lower 20 part of the duct leading to the engine, which liquid thus accumulated is wasted as it either leaks out or is carried to the engine in a mass which enriches certain charges 25 excessively and causes imperfect accumulations in the engine cylinder. By employing an auxiliary atomizer the accumulations resulting from condensation or precipitation may be reatomized as fast as they accumulate, the auxiliary atomizer having no connection 30 with any other source of fuel supply. Said auxiliary atomizer also serves the additional purpose of injecting air into the manifold at an intermediate point, thereby producing a better mixture by adding air 35 in the form of a cross current and injecting into this air any accumulations of liquid which may have collected upon the wall of the manifold. My improved device is adapted to be located at such points in the system 40 as the liquid is most liable to accumulate. For example, with a four cycle cylinder engine it is preferably placed at the lowest point in the intake pipe or manifold. With a two cycle engine it is preferably placed in 45 a crank case.

My invention is further explained by reference to the accompanying drawings, in which—

Figure 1 represents my atomizer or spraying device connected with one of the ducts leading to the power cylinder of an engine.

Fig. 2 is a top view of the atomizer removed from the duct with the upper disk and disk retaining screw removed therefrom.

Fig. 3 is a bottom view with the valve supporting sleeve removed, and

Fig. 4 is a bottom view of the device complete with the valve supporting sleeve in place.

60

Like parts are identified by the same reference numerals throughout the several views.

1 represents a duct leading to the engine with which my atomizer is used. 2 is a 65 sleeve which has threaded bearings 3 in the duct, and the same is located at the lowest point therein. 4 represents a quantity of gasoline or other heavy products of liquid fuel as it accumulates in the duct 1. The 70 upper end of the sleeve is provided with a depression or recess 5, and the same is covered by the disk 6, which disk 6 is retained in place by the screw 7. 8 is a channel which leads from the depression 5 to 75 a point below the upper surface of the liquid fuel 4. It will be understood that with each back stroke of the piston of the engine with which the duct 1 is connected a strong current of air is led into the atomizer through 80 the duct 8' formed in the hollow valve stem 9, as indicated by the arrows. The current of air passes up through the stem 9 and out through the radial ports 10, 10; thence around the sides and over the top of the 85 valve 11, and thence out through the vertical duct 12 and through the aperture 13. A small quantity of liquid 4 is drawn in through the duct 8 formed in said disk, as indicated by the dotted lines 14. As the 90 air is thus drawn through the atomizer it passes around the upper end of the valve 11 and out through the aperture 13, whereby it is caused to commingle with the liquid, whereby such liquid is discharged in a fine 95 spray which is led to the cylinder of the engine in the ordinary manner. The upper end of the valve 11 is preferably provided with a plurality of annular grooves 15, which are adapted to retain any unvaporized liquid which may incidentally drop back from the duct 12. A valve seat 16 is provided for the valve 11 and said seat is formed at the upper end of the sleeve 17. The sleeve 17 has threaded bearings 18 in 105 the inner wall of the sleeve 2. It will now be understood that with the back stroke of the piston of the engine, not shown, a current of air will be led as previously described into the atomizer through the duct 110

8', whereby the valve 11 will be lifted from its seat, when the air thus admitted will pass around the upper end of the valve and out through the duct 12 and aperture 13, as 5 stated, thereby converting the liquid fuel 4 into spray. When the piston, not shown, has completed its back stroke the valve 11 will drop back to its seat. Thus the valve 11 will be caused to rise and fall with each 10 backward and forward movement of the piston. The upward movement of the valve 11 is limited by contact with the lower end of the screw 7.

It will be understood that when the sleeve 15 2 terminates below the surface of the liquid the disk 6 and channel 8 may be dispensed with owing to the fact that the liquid when on a higher level will be brought in contact with the air as it passes through the duct 12.

20 I claim:—

1. In a device of the described class the combination of a sleeve open at one end and partially closed at its opposite end, said opposite end being provided with an aperture, 25 a valve located in said sleeve below said aperture, a disk located outside of the partially closed end of said sleeve, said disk being provided with an outlet aperture, a channel formed between said sleeve and 30 disk, an inlet air passage leading through said sleeve, and means for securing said sleeve in the wall of a duct leading to the cylinder of an engine.

2. In a device of the described class, the 35 combination of a sleeve open at its lower end and closed at its upper end, the upper end of said sleeve being provided with an outlet aperture, a valve provided with a hollow stem located in said sleeve below said aperture, one or more apertures leading from the space in said hollow stem to the space beneath said valve, a disk located above the closed end of said sleeve provided with an aperture registering with the aperture in 40 said sleeve, a channel formed in the end of said sleeve beneath said disk, said hollow 45 stem being adapted to form an inlet passage for air to said sleeve.

stem being adapted to form an inlet passage for air to said sleeve.

3. In a device of the described class, the combination of a sleeve open at its lower end and closed at its upper end, the upper end of said sleeve being provided with an outlet aperture, a valve provided with a hollow stem located in said sleeve below said aperture, the upper end of said valve being provided with a plurality of annular channels, one or more apertures leading from the space in said hollow stem to the space beneath said valve, a disk located above the closed end of said sleeve provided with an 50 aperture registering with the aperture in said sleeve, a channel formed in the end of said sleeve beneath said disk, said hollow stem being adapted to form an inlet passage 55 for air to said sleeve.

4. In a device of the described class, the combination of a sleeve open at its lower end and closed at its upper end, the upper end of said sleeve being provided with an outlet aperture, a valve provided with a hollow stem located in said sleeve below said aperture, the upper end of said valve being provided with a plurality of annular channels, a plurality of apertures leading from the space in said hollow stem to the space 70 beneath said valve, a disk located above the closed end of said sleeve provided with an aperture registering with the aperture in said sleeve, a screw for holding said disk in place on the closed end of said sleeve, the lower end of said screw being adapted to contact with and limit the upward movement of said valve, a channel formed in the end of said sleeve beneath said disk, said hollow stem being adapted to form an inlet 75 passage for air to said sleeve.

In testimony whereof I affix my signature in the presence of two witnesses.

ELMER J. MANNING.
